UNITED STATES PATENT OFFICE.

WILLIAM HENRY GREGORY GEAKE, OF KILLARA, NEAR SYDNEY, NEW SOUTH WALES, AUSTRALIA, ASSIGNOR TO WALTER RUTHERFORD, OF LONDON, ENGLAND, AND JOHN BAIN, OF OTTAWA, CANADA.

CONTAINER.

Application filed June 29, 1926. Serial No. 119,459.

This invention relates to improvements in containers, and particularly containers of the type used to contain ingredients which it is desired to dispense intermittently, particularly such materials as pastes, creams, plastics and the like, and the objects of the invention are to provide a simple, inexpensive form of extruding device operated by reciprocable motion which may be manufactured at low cost and so be available for use in containers or packages which are not to be filled, and consists essentially of the improved construction hereinafter described in detail in the accompanying specification and drawings.

In the drawings, in which like characters of reference indicate corresponding parts in all figures:

Figure 1 is a sectional elevation of an embodiment of my invention;

Figure 2 is a cross section on line 2—2 of Figure 1;

Figure 3 is a perspective view showing the end of the spring-operating member;

Figure 4 is a sectional elevation through an alternative form of the invention.

Referring to the drawings, A indicates a container of any convenient material selected with reference to the character of the material to be contained, and may, for instance, be thin sheet metal, celluloid, porcelain, glass, vulcanite or the like. In the form illustrated, the container is cylindrical and, in Figures 1 and 2, formed with a rotatable reciprocable cap B fitting the end of the container. In Figure 4 the top 10 is partly covered over and a reciprocable nozzle B' is provided. The material is designed to be extruded through a suitable orifice the outlet to which is controlled by a reciprocable member, which member also operates the extruding means. In Figure 1 the cap B constitutes the reciprocable member, and the orifice 11, through which the material is extruded, is formed in a container, said orifice being designed, when the cap is in a given position, to register with a passageway or opening 12 in the cap. The extruding means or member illustrated comprises a follower or pressure applying member C conveniently constructed of light, resilient material such as cork, and fitting closely to the inner surface of the container A, which is preferably cylindrical. This member C is operated

from the reciprocable member by a connecting or propelling member D conveniently in the form of a spiral spring which extends spirally through the member C after the manner of a corkscrew, being locked therein by a transverse pin 13 which extends between two turns of the spiral.

In order to form an intermittent or ratchet connection between the member B and the member D, an enlarged turn 14 is formed on the spring D and provided with a turning point 15 designed to engage an annular surface 16 provided on the cap B, the member D extending through an aperture 17 in the cap B and the annular surface 16 forming the bottom of a recess 18 of the cap, the top of which may be conveniently closed with a cap 19. The member D is conveniently formed of a light somewhat extending spiral spring and is preferably arranged under slight tension so that its tension will hold the cap on the container and tend to draw the member C towards the cap. The lower part of the spring extends adjacent to the bottom of the container. The cap B is preferably formed of material which the pointed end 15 of the spring may penetrate slightly as, for instance, wood, so that the pointed end and the surface 16 may constitute a ratchet connection between the spring D and the cap B.

In operating the form of the invention shown in Figure 1, the arrangement will be such that when the material is not to be used, the aperture 12 will be out of registration with the orifice 11 and may be turned for instance one-quarter or one-half a revolution away from the same. When it is desired to use the material the cap will be turned to bring the openings 11 and 12 into registration. Thus turning movement will, through the ratchet connection, turn the member D which will turn and raise the member C towards the cap B, thereby causing the material in the container to be extruded. On the return movement the point 15 will slip over the surface 16 and no material will be extruded.

In the form shown in Figure 4, the turning end 20 engages an annular or ratchet surface 21 or a reciprocable nozzle which fits in a socket 22 on the top of the container.

As many changes could be made in the above construction, and many apparently

widely different embodiments of my invention, within the scope of the claims, constructed without departing from the spirit or scope thereof, it is intended that all matter contained in the accompanying specification and drawings, shall be interpreted as illustrative and not in a limiting sense.

What I claim as my invention is:

1. In combination, a container having an orifice through which material may be extruded, an extruding member, an operating member on the container, a spiral spring forming a connection between the operating and the extruding member and having the end of the spring forming a releasable connection with the operating member.
2. In combination, a container having an orifice through which material may be extruded, an extruding member, a reciprocable member on the container, a spiral spring forming a connection between the reciprocable and the extruding member and having the end of the spring forming a releasable connection with the reciprocable member, said reciprocable member being formed with an annular engaging surface with which the spring engages.
3. In combination, a container having an orifice through which material may be ex-

truded, an extruding member, a reciprocable member having an annular surface, a spiral spring forming an operable connection between the reciprocable and the extruding members having a turned end engaging the annular surface.

4. In combination, a container, a reciprocable cap, a follower in the container and a spiral spring having a ratchet connection with the cap and extending through a spiral passage in the follower and adapted to draw the cap towards the container to seal it thereon.

5. In combination, a container, a cover member mounted thereon with freedom to turn with respect to the container and having an orifice through which the material may be extruded, a follower member in the container, a spiral spring extending through the follower member, and pawl and ratchet connecting means between the cover and the spring whereby the movement of the cover in one direction only will impart movement to the spring to thereby actuate the follower member.

In witness whereof I have hereunto set my hand.

WILLIAM HENRY GREGORY GEAKE.
